DOOR OPERATING MECHANISM

James E. Bancroft, Detroit, Mich., assignor, by
mesne assignments, to The Peelle Company,
New York, N. Y., a Corporation of New York

Application November 23, 1929
Serial No. 409,284

14 Claims. (Cl. 187—52)

This invention relates to operating mechanism for the doors of elevator hatchways, and more particularly to a power driven apparatus which will serve for all the doors of a hatchway and 5 which will open and close the doors at any floor where the elevator car is stopped.

In the operation of elevators, it is necessary because of safety regulations to fully close the doors at a given floor before the car can leave 10 this floor. It follows that under ordinary circumstances the car is held stationary for a considerable amount of time while the doors are opening and closing, and any device which will operate the doors more rapidly is of great value 15 in permitting the car to handle more passengers or more freight in the course of a day. This has been recognized, and it has heretofore been proposed to utilize a single power driven device for each hatchway and to provide means 20 for connecting this device to the door or doors at a selected floor. These prior constructions have been an improvement over the hand operation of doors, but they have not provided the rapidity of operation which is desirable, 25 they have proven to be noisy and subject to excessive wear and depreciation, and they have required a considerable amount of space in the penthouse and in the hatch.

In my prior application Serial No. 261,572, 30 filed March 14, 1928, I have disclosed a door operating mechanism which serves to transmit a substantially simple harmonic motion to the doors as they open or close, and thereby overcomes many of the defects in the earlier constructions. This mechanism is, however, of the so-called "individual" type, in which a driving 35 motor and connecting parts are provided for each set of doors, and the cost of such an installation in connection with a hatchway having a large number of doors is excessive. Moreover, where a complete door operating mechanism is used at each floor in a tall building, there is a great deal of machinery to look after and keep in repair. Because of these considerations the use of individual type operators has 40 been largely confined to buildings having a small number of floors.

It is accordingly one subject of my invention to provide a single power driven mechanism for installation in connection with an elevator hatchway having a plurality of doors which will serve to transmit a substantially simple harmonic motion to any selected door or set of doors.

50 A further object of my invention is to pro-

vide a door operating mechanism which will be simple and compact, and which can be easily installed in existing elevator installations having a large number of doors without requiring any important alterations in the existing structures. 60

A further object is to provide a door operating mechanism which cannot be damaged by the presence of an obstruction in the path of a door, and which will be self correcting when the obstruction is removed. 65

A further object is to provide a mechanism for operating elevator hatchway doors by power which will comply with all safety requirements, and which is so arranged that the car cannot leave a floor until the doors at that floor are 70 not only closed but also locked against opening from the outside, the doors cannot be opened except when the car is at the corresponding floor and they can be quickly stopped by the operator at any point in their opening or closing movement, and the locks may be easily released from inside the hatch and the doors opened by hand in the event of failure of the power supply. 75

With these and other objects in view, as will 80 be apparent to those skilled in the art, my invention resides in the combination of parts set forth in the specification and covered by the claims appended hereto.

Referring to the drawings illustrating one embodiment of my invention, and in which like reference numerals indicate like parts;

Fig. 18 is a section on the line 18—18 of Fig. 17; and

25 Fig. 19 is a side elevation showing the friction grip mechanism for one of the upper doors with its corresponding latch, the friction being shown disengaged.

30 For simplicity of illustration the invention has been shown in connection with an elevator hatchway having but two sets of doors. However, it will be clear from the following description that the invention is useful in connection with installations having a large number of sets of doors and that it is particularly adapted for such purposes.

At each floor 25 a doorway 26 is provided in the vertical wall 27 of the elevator hatchway. In the form illustrated, the openings 26 are arranged to be closed by doors of the well known counter-balanced type on the hatchway side of the wall. Each set of doors comprises an upper door 29 and a lower door 30 of substantially equal weight which are connected at each end by flexible cables 31 passing over sheaves 32 mounted on the wall 27. Each of these cables 31 is fastened to the end of a trucking bar 33 mounted along the upper edge of the lower door 30. The doors 29 and 30 are mounted to slide freely vertically in guides (not shown) and the parts are so arranged that any vertical movement imparted to one of the doors will result in a similar movement of the other door but in the opposite direction. Doors of the type described are well known in this art and are frequently operated by hand, although this method of operation is slow, inefficient and laborious.

60 In order to operate the doors by power I provide a single power actuated mechanism which may be mounted in any suitable location, such as on the floor 35 of the penthouse, and a power transmitting means which extends vertically throughout the hatchway and which may be connected to open and close any selected set of doors. These parts are preferably so arranged that as each set of doors is opened or closed it is given a substantially simple harmonic motion, which as is well known is the motion of the projection on a straight line of a point moving at a uniform velocity in a circular path. One suitable means for carrying out these purposes is illustrated in the accompanying drawings and comprises a pair of vertical cylindrical rods 36 and 37 which are arranged one at each side of the doors and which are connected at their up-

per ends by means of a flexible means such as a chain 39 extending over a pair of guides or sprockets 40. The rods 36 and 37 are likewise connected together at their lower ends by a chain 41 extending over a pair of sprockets 42 mounted on the wall 27. Those portions of the chains which do not pass over the sprockets during the operation of the mechanism may be replaced by rigid rods as illustrated and a turnbuckle 43 is preferably provided in the lower chain 41 in order to take up any slack which may occur. The rods and chains thus form a continuous power transmitting circuit. The sprockets 40 are connected by means of shafts 45 (Fig. 3) to a second pair of sprockets 46 around which passes a chain 47. A part of the upper portion of the chain 47 is replaced by a rigid bar 50 slidably lengthwise of itself in suitable guides 51. This bar 50 is joined by means of a connecting rod 52 to a crank arm 53. The crank arm 53 is driven by means of an electric motor 55 through a worm and worm gear reduction 56. The revolution of the crank arm is what produces the simple harmonic motion imparted to the doors.

In order to stop the motor 55 immediately whenever the electric current supply thereto is interrupted, I preferably provide on the shaft between the motor and the worm gear reduction 56 a solenoid released brake 57 (Fig. 3) having a coil 58 (Fig. 11). Brakes of this general type are well known to the art and one suitable construction is disclosed in the patent to Peelle No. 1,410,271.

It will be noted that in Fig. 1 the crank arm 53 is shown in one dead center position. As this crank arm is revolved by the motor in the direction of the arrow this will cause the bar 50 to slide to the right, and the sprockets 46 and 40 will rotate in a clockwise direction thus moving the rod 36 downwardly and the rod 37 upwardly. When the motor is reversed the crank arm will move in the opposite direction and the rod 36 will be raised and the rod 37 lowered to its original position. The length of the crank arm and the ratio of the sprockets is such that as the crank arm moves from one dead center position to the other the rods 36 and 37 will travel vertically a distance equal to the desired movement of the doors, and the rods will be started and stopped gradually in accordance with the simple harmonic motion imparted thereto.

110 In order to transmit the vertical movement of the rods 36 and 37 to the doors, I provide a suitable mechanism for connecting any selected set of doors to the rods. This mechanism is preferably so arranged that it will only connect a set of doors when the elevator car is stopped adjacent to the corresponding floor. For this purpose I provide a friction grip device or clutch 59 which is mounted upon the right hand end of the trucking bar 33 of each lower door (Fig. 1) and which is arranged to frictionally engage the rod 36 whenever it is actuated by means of a cam 60 mounted upon the elevator car 61. Each friction grip device 59 comprises a casing 63 mounted on the trucking bar 33 and provided with a semi-circular groove lined with suitable friction material 64, such as leather or rubber, (Fig. 16) which is shaped to fit against the rod 36. This rod 36 is arranged to be clamped between the casing 63 and an adjustable shoe 65 having a similar semi-circular groove therein which is lined with friction material 66.

The shoe 65 is preferably thrown into engagement with the rod by means of a self-locking or over-center toggle. For this purpose I provide a shaft 68 which is rotatably supported 5 in bearings in the casing 63 and carries at one end an arm 69 supporting a roller 70 arranged to be engaged by the cam 60. The shaft 68 also carries a short arm 72 which is connected to a bar or plate 73 by means of a link 74. A pair 10 of compression springs 76 are located between the plate 73 and the shoe 65. These springs 76 preferably surround pins 77 fixed in the shoe 65 and extending through openings in the plate 73. Cotters 78 through the ends of the pins 77 hold 15 these parts in assembled relation and serve to receive the pressure of the springs 76 when the friction grip is released.

It will now be seen that when the roller 70 is moved by the cam 60 from the position shown 20 in Fig. 14 to that shown in Fig. 15, the shaft 68 is rotated in a counter-clockwise direction. The arm 72 and the link 74 form a toggle connection and serve to first move the plate 73 and shoe 65 to the right and against the rod 36 and then to compress the springs 76 and apply a 25 substantial pressure against the rod 36, gripping the rods between the shoe 65 and the casing 63. It will also be seen from an inspection of Fig. 17 that when the toggle mechanism applies the 30 gripping pressure it passes slightly beyond its center position and is, therefore, made self-locking by the pressure of the springs 76. Counter-clockwise rotation of the shaft 68 is limited by a stop 80 integral with the arm 69 and arranged to engage against the trucking bar 33 shown in Fig. 15 when the friction grip is applied.

It is desirable from a safety point of view to 40 lock the doors together in their closed position and thereby prevent anyone from opening the doors manually from a point outside the hatchway. For this purpose I mount on the right hand side of each upper door 29 (Fig. 1) a bar 45 81 which extends beyond the edge of the door and carries on its outer end a bracket 82 (Figs. 14 and 15), on which is pivotally mounted a latch or hook-shaped member 83. The latch member 83 is pivoted to the bracket 82 at 85 and is arranged to hook beneath the trucking bar 33 on the lower door when the doors are closed, as clearly shown in Fig. 14. The latch 50 83 is urged toward latching position by means of a powerful compression spring 86. The spring 86 bears against a lug 87 on the bracket 82 and this lug also serves as a stop to prevent the latch 83 from swinging beyond the position shown in Fig. 14 after the doors have been 55 opened. In order to release the latch when the friction grip is applied as a preliminary step in the opening of the doors, I provide a projecting portion 89 on the arm 69 which is arranged to force the member 83 into the position shown in Fig. 15 when the friction grip is applied. When 60 the doors start to open under the influence of the friction grip, the latch member 83 will travel upwardly with the door 29 and slide over the surface of the trucking bar 33 which is moving downwardly with the lower door. When the 65 doors are again closed the member 83 will travel downwardly with the upper door and because of the cam shaped curved surface 90 at its lower end it will simply ride up over the trucking bar and snap into place as shown in Fig. 14.

75 The spring 86 is made sufficiently powerful so

that when the cam 60 is out of the way it will force the latch 83 into latching position and push back on the projecting portion 89 of the arm 69, thereby releasing the self-locking toggle of the friction grip mechanism. In order to insure that the friction surfaces will not drag against the rod 36 after it is released, I provide a weighted portion 91 on the arm 69 which after the release of the toggle will serve to rotate the shaft 68 in a clockwise direction into the position shown in Fig. 14 and bring the arm 72 against a stop 92 (Fig. 16) on the casing 63.

It is desirable to connect the other end of each upper door to the power actuating mechanism in the penthouse, and for this purpose I mount 80 on each upper door 29 and adjacent the lower left hand corner thereof a bar 94 which is similar to the bar 81 on the right hand side thereof. Each bar 94 carries on its outer end a friction grip device 95 (Fig. 19) which is exactly similar to the device 59 mounted on the bar 81 except that the device 95 is arranged the other side up. Because of this reversal in position the arm 96 thereon does not require a weighted portion equivalent to the part 91 on the arm 69, 100 since the weight of the roller 98 serves to normally hold the friction released. Each arm 96 is provided with a stop 99 and a projection 100 which are similar to the parts 80 and 89 respectively on the arm 69.

I prefer to provide means for locking the doors to some stationary part of the structure when in a closed position as well as latching them together in the manner shown in Fig. 14. For this purpose I provide a supporting bracket 102 (Fig. 19) which is mounted upon any suitable part of the stationary structure such as the door guide rail 103 located adjacent to the vertical edge of the door. A latch member 104 is pivoted to the bracket 102 by means of the pin 105 and is urged toward latching position by means of a compression spring 107. A stop 108 on the upper portion of the member 104 limits the movement imparted to it by the spring 107. This latch member 104 overlies the bar 94 on the upper door when the doors are in closed position and thus normally prevents opening thereof. When the friction grip device 95 is engaged by means of a cam 109 (similar to cam 60) on the elevator car 61, the projection 100 contacts with the member 104 and releases the latch thus permitting the part 94 to move upwardly and the doors to be opened. When the doors are again moved toward closed position, the bar 94 strikes against a sloping cam surface 110 on the latch member 104 and thus compresses the spring 107 until the doors have reached their fully closed position, when the latch will snap back into the position shown in Fig. 19. The spring 107 is sufficiently 115 powerful to release the self-locking toggle of the friction grip mechanism unless the cam 109 prevents it.

The cams 60 and 109 may be fixed in a definite position on the elevator car, but I prefer to so arrange these parts that the cams will retire out of their operative position except when it is desired to open the doors, so that they will not affect the friction grip devices at a floor which the car passes without stopping. For this purpose I mount each cam 60 and 109 on the elevator car by means of pivoted links 112 (Fig. 2) so that as each cam is moved upwardly it will also move outwardly away from the elevator car and into the operative position shown in Fig. 2. While these cams may be actuated manually, I

prefer to actuate them by power, and for this purpose I utilize an electric motor of the so called "torque" type which is arranged to be stalled on the line. This torque motor 113 is mounted on the under side of the elevator car 61 and drives a rotatable shaft 114 through a chain and sprocket connection 116. This shaft 114 is mounted in suitable bearings 117 on the under side of the elevator car and carries at each end a crank arm 118. These crank arms 118 are joined to the cams by means of suitable connecting rods 120. Whenever the torque motor 113 is energized it serves to rotate the shaft 114 in a clockwise direction as viewed in Fig. 2, and the shaft will turn in this direction until its motion is limited by an arm 121 keyed to the shaft. This arm serves as a stop for the shaft by striking against a switch 122 mounted on the car 61, as shown in detail in Fig. 8, and at the same time serves to close this switch, which is normally held open by a spring 123. The closing of the switch 122 serves to start the motor 55 in the penthouse to open the doors in a manner to be hereinafter described.

It is necessary that the shaft 114 should reach the limit of its movement so as to close the switch 122, and in order that this may occur despite irregularities in alignment of the various friction grip devices I preferably make each connecting rod 120 slightly compressible. One suitable way of accomplishing this purpose is disclosed in Fig. 4. As there illustrated the upper portion 125 of each connecting rod 120 is slideable relative to the remainder of the rod and is normally held in an extended position by a compression spring 126. This spring 126 is made sufficiently strong so that the friction grip device will be forced into a full engagement and if after this has happened the switch 122 has not been closed the spring 126 will compress slightly so as to permit the shaft 114 to rotate the additional amount required to close the switch.

It will be seen from Fig. 2 that each crank arm 118 approaches one dead center position as the cams 60 and 109 reach their fully extended positions. This gives a toggle effect to the mechanism and amplifies the force which is transmitted to engage the friction grip devices. The arm 121, however, prevents the crank arms 118 from quite reaching their dead center position, and as a result when the torque motor 113 is deenergized the cams 60 and 109 will descend upon the action of gravity into an inoperative position, the torque motor being rotated in a counter-clockwise direction by the weight of the cams.

In order to prevent any possibility of power actuation of the doors except when the elevator car is stopped at a landing, I provide a zone switch 128 (Figs. 9 and 10) which is mounted upon the side of the car 61 and is included in the door control circuit. This switch 128 is arranged to be closed by an arm 129 pivoted at its lower end to the car and provided at its upper end with a roller 130. A cam 132 is mounted on the hatchway wall at each floor and arranged to contact with the roller 130 when the car is at that floor and thereby close the switch 128. When the car is not at a floor the switch is held open by the weight of the roller 130 and arm 129.

In order to stop the door actuating motor 55 whenever the doors reach either their fully open or fully closed position, I provide the limit switches 133 and 134, illustrated in detail in

Fig. 7, which are in the motor control circuit. These switches are normally held closed by means of compression springs 135 and 136 respectively and are opened by means of arms 138 and 139 mounted on the shaft 140 which drives the crank arm 53 in the penthouse. These parts are so arranged that at the instant the crank arm 53 reaches either of its dead center positions one of the limit switches 133 or 134 will be opened, as shown in Fig. 7.

Various types of motors may be used in connection with my invention but in the wiring diagram (Fig. 11) I have shown the motors 55 and 113 as of the compound wound type intended for use with a direct current supply. The main switches which control the current flow to the motors are preferably of the well known solenoid actuated type which normally remain open under the influence of gravity and are closed by the action of an energized solenoid. I utilize two three-pole switches 142 and 143 to control the current to the door actuating motor 55. The first of these may be closed by a solenoid 144 to operate the motor in a direction to open the doors, and the latter may be closed by a solenoid 145 and serves to operate the motor 55 in a direction to close the doors. Since the torque motor 113 is not reversible a single two-pole switch 147 arranged to be closed by a solenoid 148 serves to control the current supply to this motor.

As illustrated in Fig. 5 the switches 143 and 147 may comprise switch arms 150 and 151 respectively which are pivotally mounted on opposite sides of a supporting and insulating panel 152. The switch arms 150 and 151 carry contact members 154 and 155 respectively which, when the switch is closed, engage with other contact members 156 and 157 mounted on the panel. In Fig. 5 switch 143 is shown open and switch 147 closed. It is thought unnecessary to illustrate switch 142 as it is constructed in a similar manner to switch 143, except that it does not have the interlocking construction to be hereinafter described.

In connection with the switches 143 and 147, I preferably utilize the construction shown and described in my prior application Serial No. 312,095 filed October 12, 1928. This construction mechanically interlocks the switches so as to prevent their simultaneous closure and also provides further advantages which will be herein-after apparent. As shown in Fig. 6, I provide an interlocking bar 159 having bluntly pointed ends which is pivotally mounted centrally at 160 in the panel 152. This bar 159 is normally but yieldingly held in a horizontal position by means of a coiled spring 161. The switch arms 150 and 151 carry interlock fingers 163 and 164 respectively. These fingers carry near their upper ends small insulated blocks 165 and 166, having notches in their faces.

These parts are so shaped and arranged that when for instance the switch 147 is closed, the switch movement will cause the finger 164 to contact with the bar 159 and raise its right hand end, while at the same time lowering its left hand end into the path of the insulated block 165, but not in contact therewith. The electrical contact between the finger 164 and the bar 159 maintains the circuit through the solenoid 148, as will be hereinafter explained. The bar 159 in its new position prevents closure of the switch 143, and if the solenoid 145 should be energized in an attempt to close the switch 143, the insu-

lated block 165 would strike against the bar 159 and result in tipping it still farther, thus breaking its contact with the finger 164, and deenergizing the solenoid 148, whereupon switch 147 will open. A similar result will be reached if an attempt is made to close switch 147 while switch 143 is closed.

In order to provide a manual control for the motor 55 and the doors actuated thereby, I preferably provide a pair of manually operated switches or push buttons 166 connected in parallel as shown in Fig. 10 and a further pair of push buttons 167 likewise connected in parallel. One push button 166 and one push button 167 are mounted in the elevator car and the others are preferably located at a point outside the hatchway at the ground floor of the building. It will be apparent that additional push buttons may be connected in parallel with those shown and located at other convenient places as desired.

The operation of the various parts as so far described will now be explained with particular reference to the wiring diagrams shown in Figs. 10 and 11. First assume the elevator car is brought to a stop adjacent one of the landing floors 25. As soon as the car reaches the landing the cam 132 (Fig. 9) adjacent this landing contacts with the roller 130 on the car and closes the zone switch 128. The doors, of course, have been previously closed and latched by the mechanism shown in Figs. 14 and 19. The operator now wishing to open the doors presses push button 167 on the car, thereby closing a circuit from electric power source 168 through zone switch 128, through limit switch 134, which is held closed by spring 136 (Fig. 7) at all times except when the doors are fully open, through solenoid 148 and then back through push button 167 to the other side 169 of the power supply. The instant that solenoid 148 is energized, switch 147 is pulled by the solenoid into the closed position, and at the same time interlock finger 164 contacts with interlock bar 159 thus closing a circuit back to power source 169 independent of the circuit through push button 167 and permitting the release of this push button without resulting in a deenergization of solenoid 148. The closure of switch 147 connects torque motor 113 directly across power supply 171, 172 (Fig. 11). This power supply may be the same as 168, 169 or independent thereof. Switch 147 having been closed the torque motor 113 rotates shaft 114 in a clockwise direction (Fig. 2) and moves the retiring cams 60 and 109 into operative position. These cams contact with rollers 70 and 98 and cause the friction grip devices 59 and 95 to engage the vertical rods 36 and 37. At the same time the arm 121 swings with the shaft 114 and strikes the action switch 122 closing this switch and stalling the torque motor, though the current supply to the motor is not interrupted. Closure of the switch 122 connects the solenoid 144 in parallel with the energized solenoid 148, as shown in Fig. 10, thereby energizing solenoid 144 and pulling switch 142 into closed position. This completes a circuit from the power source 171 through the left pole of switch 142, through the armature of the pent-house motor 55, through the center pole of switch 142, through the series field of motor 55, and then through right pole of switch 142 back to the other side 172 of the line. At the same time a circuit is completed from power source 171 through the shunt field of the motor field

55, through the right pole of switch 142 and back to the other side 172 of the line. At the same time as the shunt field is energized the brake coil 58 connected in parallel therewith is likewise energized and the brake on the motor shaft is released.

The motor 55 will immediately start rotating the crank arm 53 in the direction shown by the arrow in Fig. 1, thereby causing rod 36 to move downwardly and rod 37 to move upwardly. Since these rods have been connected to the doors by the friction grip devices, the lower door 30 will be pulled downwardly and the upper door 29 will be pulled upwardly. Because of the use of the crank arm 53 and connecting rod 52 starting and stopping on the dead center positions a substantially simple harmonic motion will be imparted to the doors. The doors will start slowly giving the motor ample opportunity to pick up speed without overloading and the doors will accelerate to high speed and then gradually slow down to a gradual stop without slamming. Because of the slow starting features there is no yanking on the rods 36 and 37 and very little tendency for the rods to slip through the fric- 100 tions. As soon as the crank arm 53 reaches its other dead center position and the doors are fully open, arm 139 (Fig. 7) will reach such a position as to open the limit switch 134. This deenergizes solenoids 148 and 144 as will be clear 105 from Fig. 10, and causes switches 147 and 142 to open. The opening of these switches breaks the power supply to both the motors. Motor 55 will be brought to an immediate stop by the action of the brake 57, and torque motor 113 will 110 be reversed by the weight of the retiring cams 60 and 109. It will be seen that as the doors move toward open position the rollers 70 and 98 will soon run off from the retiring cams. This, however, does not permit the release of the 115 friction grip devices, since a self-locking toggle mechanism is incorporated in them as heretofore explained.

Assume now that the elevator operator wishes to close the doors and leave the floor. He 120 presses push button 166 on the car thereby completing a circuit from power supply 168 through zone switch 128, through limit switch 133, which was closed by spring 135 immediately after the doors started to open, through solenoid 145, 125 through push button 166 and thus back to the other side 169 of the line. Energization of the solenoid 145 pulls switch 143 into the closed position at the same time bringing interlock finger 163 into contact with interlock bar 159 and thus completing a circuit back to power supply 169 independent of push button 166 which may now be released without deenergization of solenoid 145. Closure of switch 143 completes a circuit 130 from power supply 171 through the left pole of switch 143, through the armature of motor 55, through the center pole of switch 143, through the series field of motor 55, and through the right pole of switch 143 back to the other side 172 of the line. At the same time the shunt field of motor 55 and the brake solenoid 58 are connected directly across the line through the right pole of switch 143. It will be seen that under these conditions the direction of current flow through the motor armature is in a direction contrary to that occurring when switch 142 is closed, while the flow through the field windings is the same. The motor 55 will therefore start in the opposite direction. The crank arm 53 will be revolved in a direction opposite to the 135 140 145 150

arrow in Fig. 1, and the doors will be moved with a simple harmonic motion to the closed position. As the crank shaft 53 reaches its dead center position and the doors are fully closed, arm 128 will open limit switch 133 thus deenergizing solenoid 145 and opening switch 143, and the motor 55 will be immediately stopped by the action of brake 57.

If the doors are moving toward closed position and it is desired for any reason to stop their movement, it is merely necessary to press push button 167 (which is the one used for opening the doors) thus energizing solenoid 148. Because of the interlock bar 159, the corresponding switch 147 cannot be closed but the switch arm 151 will nevertheless move slightly and the block 166 on the interlock finger 164 will strike the interlock bar 159 which is already deflected by the interlock finger 163 and deflect this bar still more. This will break the contact between interlock finger 163 and interlock bar 159 and deenergize solenoid 145 causing switch 143 to open and the motor 55 to stop. In a similar manner the doors may be stopped during their opening movement merely by pressing the other push button 166. Once the movement of the doors has been stopped, they can be started again in either direction desired merely by pressing the proper push button.

Because of the simple harmonic motion with its gradual start and stop features, the friction grip devices may be so designed that they will slip in the event one of the doors meets an obstruction during its movement and thereby prevent damage to the driving mechanism. If the doors were given a sudden start, as has been the custom in prior constructions, the friction grips would have to engage the rods very firmly indeed to prevent slipping because of the inertia of the doors. With the construction of the present invention, if the frictions should slip due to an obstruction they would slip again when the doors came up against their stops at the end of the door travel; the mechanism is therefore self-correcting and the doors will operate in the proper manner at their next opening or closing movement. The entire mechanism is balanced and the only forces to be overcome are those of friction and inertia. The weight of the rod 36 is exactly balanced by the weight of the rod 37 no matter how many floors there are in the building, and the weight of each lower door 30 is exactly balanced by the weight of the corresponding upper door 29. In the event of failure of the power supply, the latches can be easily released from inside the hatchway and the doors then opened by hand.

A further feature of my invention involves the use of a master interlock switch which is so constructed and arranged that the doors must not only be closed but also locked from inside of the hatchway before the elevator car can leave a landing. In the embodiment illustrated this master interlock is actuated by the latch members 83 shown in detail in Figs. 14 and 15. As there illustrated, an interlock arm 175 is pivotally mounted at 176 on each bracket 82. Each arm 175 has integral therewith a pair of lugs 177 which straddle an upstanding lug 179 formed on the latch member 83. These parts are so arranged that whenever the latch 83 is released to permit opening the doors the arm 175 will swing about its pivot in a clockwise direction into the position shown in Fig. 15. A vertical member, such as a wire 180, extends the

length of the hatchway through the ends of the arms 175 and this wire carries a stop 181 adjacent each interlock arm. As the arm 175 moves into the position shown in Fig. 15 it raises the adjacent stop 181 and the wire 180 against the action of a weight 183 mounted on the lower part of the wire (Fig. 1). I utilize this upward movement of the wire 180 to open an electric circuit and prevent movement of the elevator car.

For this purpose I provide the interlock switch illustrated in Figs. 12 and 13. As shown in Figs. 12 and 13, this switch comprises a pair of spring contacts 184 and a movable contact member 185 which is carried by an arm 187 mounted on a shaft 188. This shaft 188 is rotatably supported in suitable bearings in a case 189 and carries on its outer end a cam member 191. A sprocket 192 is rotatably supported on the casting 189 and a chain 193 extends from the upper end of wire 180 and around the sprocket 192 as shown in Fig. 1. The right hand end of chain 193 is connected by a wire 195 (Fig. 1) to a second chain 196 which passes around a sprocket 197 at the lower end of the hatchway and connects to the lower end of wire 180. The chain 193 has a special projecting link 199 (Fig. 12) which normally extends into a notch 200 in the cam member 191.

The operation of this master interlock switch will now be apparent. The contact members 184 are connected into the control circuit for the elevator car in a manner well known to those skilled in the art. Whenever the interlock wire 180 is raised by the releasing of any one of the latch members 83 the projecting link 199 will act on the cam 191 and rotate the shaft 188 in a counter-clockwise direction. This will break the contact between the member 185 and the left contact member 184, thus preventing operation of the elevator. When the doors are opened the wire 180 will travel upwardly with them for the full distance and the link 199 of course will leave the groove in the cam 191 and travel downwardly at the right hand side of sprocket 192. The interlock switch will be held in the open position by the friction of the right contact member 184 with the member 185. When the doors are closed and latched the weight 183 will cause the special link 199 to move upwardly, enter the notch 200 in the cam 191 and move the switch into the closed position shown in Figs. 12 and 13, thus permitting operation of the elevator.

Having thus described my invention, what I claim as new and desire to secure by Letters Patent is:

1. An operating mechanism for the slideable doors of an elevator hatchway having an elevator car therein comprising a power transmitting means extending vertically of the hatchway, a power actuated crank, means including a connecting rod pivoted to the crank and arranged to move the power transmitting means vertically, means affected by the position of the elevator car and arranged to connect the power transmitting means to any one of said doors when the elevator car is stopped adjacent thereto, and means to stop the movement of said crank as it reaches either of its dead center positions.

2. An operating mechanism for the slideable doors of an elevator hatchway having an elevator car therein comprising an electric motor, a crank actuated thereby, a connecting rod pivoted to the crank, and means to transmit power from the connecting rod to any one of said doors.

- when the elevator car is stopped adjacent thereto, said means including a yieldable connection which will transmit a predetermined force only to the door and which will yield and prevent damage in case said predetermined force is exceeded. 5
3. An operating mechanism for a series of slideable elevator doors comprising a power transmitting member movable vertically of the elevator hatchway, door gripping devices on the doors frictionally engageable with said member for moving the doors, a single electric motor for moving the member, a crank arm and connecting rod driven by the motor, and means including a starting switch and a limit switch to operate the motor and rotate the crank arm through substantially a single half turn from one dead center position to the other, said connecting rod being so connected to said member that the crank arm is on dead center when the doors are both fully opened and closed. 10
4. An operating mechanism for the vertically slideable counterbalanced doors of an elevator hatchway having an elevator car therein comprising two vertically movable power transmitting members mounted in the hatchway, one at each side of the doors, flexible means directly connecting the upper ends of the members, additional flexible means directly connecting the lower ends of the members to provide a continuous power transmitting circuit, guides for said flexible means, means effective when the elevator car is stopped adjacent to a set of doors to connect the upper door of the set to one of said members and the lower door to the other of said members, a motor driven crank, and means including a connecting rod pivoted to the crank which transmits power to said circuit and causes the members to move with a substantially simple harmonic motion as the crank moves from one dead center position to the other. 15
5. A door operating mechanism for the doors of an elevator hatchway comprising two rods mounted for vertical movement in the hatchway and frictional engagement with door opening devices, a flexible connecting member between the upper ends of the rods, guides therefor, a crank arm and connecting rod, a power driven mechanism, a control device to operate the mechanism through a definite cycle and move the crank arm from one dead center position to the other, and connections between the crank driven connecting rod and the flexible connecting member, said parts being so arranged that the doors are fully opened and closed when the arm is substantially on its dead center positions. 20
6. A door operating mechanism for the doors of an elevator hatchway comprising two rods mounted for vertical movement in the hatchway and frictional engagement with door opening devices, a flexible connecting chain between the adjacent ends of the rods, sprockets supporting the chain, one of which serves as a driver to move the rods, a power driving mechanism, and connections between the mechanism and the driving sprocket to move the rods. 25
7. A door operating mechanism for the doors of an elevator hatchway comprising two rods mounted for vertical movement in the hatchway and frictional engagement with door opening devices, a flexible connecting chain between the adjacent ends of the rods, sprockets supporting the chain, one of which serves as a driver to move the rods, a power driven mechanism, a crank arm and connecting rod driven thereby, a control device to rotate the crank from substantially one dead center position to the other, and means whereby the connecting rod is connected to rotate said driving sprocket, said parts being so arranged that the crank arm is substantially on its dead centers when the doors are fully open and closed. 30
8. A door operating mechanism having a vertically slideable rod and a friction grip device engageable therewith comprising a gripping member having a friction surface adjacent to one side of the rod, a friction shoe movably mounted on the other side of the rod, and means including a toggle linkage arranged to move the shoe and thereby grip the rod between the shoe and said friction surface. 35
9. A door operating mechanism having a vertically slideable rod and a friction grip device engageable therewith comprising a gripping member having a friction surface adjacent to one side of the rod, a friction shoe movably mounted on the other side of the rod, a toggle linkage, and a spring connecting the linkage with the shoe, the linkage being arranged to move the shoe into contact with the rod and grip the rod between the shoe and said friction surface, and the spring serving to lock the toggle in the over-center position when the shoe is in gripping position. 40
10. In combination with a series of doors mounted adjacent to openings in the wall of an elevator hatchway in which an elevator car is movable, a latch adjacent to each door arranged to lock the door in its closed position, a master interlock switch, and connecting means between each latch and the switch which is so arranged that release of any one of the latches will open the switch and prevent operation of the elevator car. 45
11. In combination with a series of doors mounted adjacent to openings in the wall of an elevator hatchway in which an elevator car is movable, a latch adjacent to each door arranged to lock the door in its closed position, an interlock arm connected to each latch and arranged to be moved thereby, a member extending vertically of the hatchway and having a stop adjacent each interlock arm, and a master interlock switch connected for actuation by said member, said parts being so constructed and arranged that release of any one of the latches will open the switch and prevent operation of the elevator. 50
12. An operating mechanism for the doors of an elevator hatchway having an elevator car therein comprising a power transmitting rod extending vertically of the hatchway, an electric motor, a rotatable member driven by the motor, connecting means between the member and the rod, said connecting means and the rotatable member having two dead center positions, connecting mechanism adjacent to each door arranged to connect the door with the rod, means affected by the position of the elevator car and arranged to render each connecting mechanism effective only when the car is stopped adjacent thereto, an electric switch to start the motor, and a limit switch to stop the motor as the rotatable member reaches either dead center position, whereby the doors are moved through a predetermined distance with a linear velocity which smoothly and gradually approaches zero at each limit of travel. 55
13. An operating mechanism for the vertically slideable counter-balanced doors of an elevator hatchway having an elevator car therein comprising a power transmitting rod extending vertically of the hatchway, an electric motor, a rotatable member driven by the motor, connecting means between the member and the rod, said connecting means and the rotatable member having two dead center positions, connecting mechanism adjacent to each door arranged to connect the door with the rod, means affected by the position of the elevator car and arranged to render each connecting mechanism effective only when the car is stopped adjacent thereto, an electric switch to start the motor, and a limit switch to stop the motor as the rotatable member reaches either dead center position, whereby the doors are moved through a predetermined distance with a linear velocity which smoothly and gradually approaches zero at each limit of travel. 60
14. An operating mechanism for the vertically slideable counter-balanced doors of an elevator hatchway having an elevator car therein comprising a power transmitting rod extending vertically of the hatchway, an electric motor, a rotatable member driven by the motor, connecting means between the member and the rod, said connecting means and the rotatable member having two dead center positions, connecting mechanism adjacent to each door arranged to connect the door with the rod, means affected by the position of the elevator car and arranged to render each connecting mechanism effective only when the car is stopped adjacent thereto, an electric switch to start the motor, and a limit switch to stop the motor as the rotatable member reaches either dead center position, whereby the doors are moved through a predetermined distance with a linear velocity which smoothly and gradually approaches zero at each limit of travel. 65
15. An operating mechanism for the vertically slideable counter-balanced doors of an elevator hatchway having an elevator car therein comprising a power transmitting rod extending vertically of the hatchway, an electric motor, a rotatable member driven by the motor, connecting means between the member and the rod, said connecting means and the rotatable member having two dead center positions, connecting mechanism adjacent to each door arranged to connect the door with the rod, means affected by the position of the elevator car and arranged to render each connecting mechanism effective only when the car is stopped adjacent thereto, an electric switch to start the motor, and a limit switch to stop the motor as the rotatable member reaches either dead center position, whereby the doors are moved through a predetermined distance with a linear velocity which smoothly and gradually approaches zero at each limit of travel. 70
16. An operating mechanism for the vertically slideable counter-balanced doors of an elevator hatchway having an elevator car therein comprising a power transmitting rod extending vertically of the hatchway, an electric motor, a rotatable member driven by the motor, connecting means between the member and the rod, said connecting means and the rotatable member having two dead center positions, connecting mechanism adjacent to each door arranged to connect the door with the rod, means affected by the position of the elevator car and arranged to render each connecting mechanism effective only when the car is stopped adjacent thereto, an electric switch to start the motor, and a limit switch to stop the motor as the rotatable member reaches either dead center position, whereby the doors are moved through a predetermined distance with a linear velocity which smoothly and gradually approaches zero at each limit of travel. 75

hatchway having an elevator car therein comprising two vertically movable power transmitting members mounted in the hatchway, a rotatable member, connecting means between the rotatable member and the power transmitting members to move said members simultaneously in opposite directions, said connecting means and the rotatable member having two dead center positions, and means effective when the elevator car is stopped adjacent to a set of doors to connect the upper door of the set to one of said power transmitting members and the lower door to the other of said power transmitting members, the dead center positions of the rotatable member corresponding to the extreme positions of the doors, whereby the doors are moved through a predetermined distance with a linear velocity which smoothly and gradually approaches zero at each limit of travel.

14. An operating mechanism for the doors of

an elevator hatchway having an elevator car therein comprising a power transmitting means extending vertically of the hatchway, a rotatable member, connecting means between the member and the power transmitting means arranged to raise and lower the power transmitting means, said connecting means and the rotatable member having two dead center positions, a friction clutch adjacent to each door arranged to connect the power transmitting means thereto, and means effective when the elevator car is stopped adjacent to a door to cause engagement of the corresponding clutch, the dead center positions of the rotatable member corresponding to the extreme positions of the doors, whereby the doors are moved through a predetermined distance with a linear velocity which smoothly and gradually approaches zero at each limit of travel.
